Unpublished Design U.S. Appl. No. 29/390,985, filed May 2, 2011, first named inventor Richard G. Tuck.

Primary Examiner — Kevin Rudzinski

(74) Attorney, Agent, or Firm — Porter, Wright, Morris & Arthur, LLP

(57) **CLAIM**

The ornamental design for a light fixture, as shown and described.

DESCRIPTION

FIG. 1 is a perspective view of a light fixture according to a first embodiment of my new design;

FIG. 2 is another perspective view thereof;

FIG. 3 is a top view thereof;

FIG. 4 is a bottom view thereof;

FIG. 5 is front view thereof;

FIG. 6 is rear view thereof;

FIG. 7 is a right side view thereof;

FIG. 8 is a left side view thereof;

FIG. 9 is a perspective view of a light fixture according to a second embodiment of my new design;

FIG. 10 is another perspective view thereof;

FIG. 11 is a top view thereof;

FIG. 12 is a bottom view thereof;

FIG. 13 is front view thereof;

FIG. 14 is rear view thereof;

FIG. 15 is a right side view thereof; and,

FIG. 16 is a left side view thereof.

The dashed lines in the figures form no part of the claimed design and are included to show environment.
